(57) **CLAIM**

The ornamental design for a track assembly as shown and described.

DESCRIPTION

FIG. 1 is a left side elevational view of a track assembly showing our new design;

FIG. 2 is a right side elevational view of the track assembly of FIG. 1;

FIG. 3 is a left side perspective view of the track assembly of FIG. 1;

FIG. 4 is a right side perspective view of the track assembly of FIG. 1;

FIG. 5 is a top elevational view of the track assembly of FIG. 1; and,

FIG. 6 is a bottom elevational view of the track assembly of FIG. 1.

Throughout the Figures, where shown, the dashed lines are included for the purpose of illustrating portions of the article which form no part of the claimed design.

1 Claim, 6 Drawing Sheets
